UNITED STATES PATENT OFFICE

2,523,845

GATE LATCH

Walter Francis Roseburrough, Newton, Iowa

Application November 13, 1946, Serial No. 709,588

5 Claims. (Cl. 292—108)

1

This invention relates to improvements in gate latch and has particular reference to a latch suitable for securing the free edge of a hinged gate to a stationary member.

The principal object of this invention is the provision of a gate lock wherein the latch is normally secured in the latched position and can not be released by engaging and raising the latch member.

Another object of the present invention is the provision of a gate latch constructed and operable in such a manner that it can not be easily opened by children or trained farm animals.

Other objects are sturdiness and economy of construction, efficiency of operation and suitability for securing the various types of horizontally hinged closure members.

With these objects in view, as well as other objects, which will appear during the course of the specification, reference will be had to the drawing wherein:

Figure 1 is an elevational view of a gate latch mounted on a gate structure, shown secured in solid lines and released in dotted lines, and embodying this invention.

Fig. 2 is an enlarged elevational view of the latch bar.

Fig. 3 is a plan view of the latch bar shown in the securing position.

Fig. 4 is a fragmentary elevational view showing the latch member in the released position.

Throughout the several views like reference characters refer to similar parts and the numeral 10 designates a latch assembly having a base plate 12 provided with corner opening 14 adapted to receive screws 16 by means of which the plate is secured to the stile of a hinged gate 18. The latch bar 20 is pivoted by means of shouldered rivet 22 to plate 12 and has a notch 24 at its outer free end to engage one leg 26 of a staple 28 which is securely anchored in a stationary fence member 30 adjacent the opening which the gate is adapted to close. The extremity of the latch passes through the staple 28 as clearly shown.

The upper inner portion of latch 20 is arcuate at 32 while the lower portion is diagonally formed to present an outwardly projecting tongue 34 disposed below the axis of rotation of the latch.

Referring to Figure 2 it will be noted that a cam member 36 is pivotally mounted by shouldered rivet 38 to the base plate 12 for limited rotation. The latch 20 is normally positioned to the horizontal when in the latched position, and the axis of rotation is in substantially horizontal

2

relation with the upper edge of 20. The periphery 40 of the cam is circular for about 270° and fits snugly into the arcuate recess 32 of latch bar 20 to secure the latch against movement on its axis so long as the arcuate parts are in operative relation.

A substantially radially disposed boss 42 extends outwardly from the circular periphery 40 to form a stop to rest against the upper side of bar 20 thereby limiting the rotation of the cam in one direction. The periphery of the cam is recessed at 44 intermediate boss 42 and the circular cam section 40, for reasons hereinafter set forth.

15 An operating arm 46 is welded or otherwise securely attached to the outer surface of cam member 36 whereby the cam is manually rotated to release and raise the latch arm 20. Arm 46 is offset outwardly at 48 whereby the hand 20 gripping portion of said arm is spaced outwardly from the latch 20 and the post 30 a sufficient distance to permit free action of the arm.

When the latch means is in the position shown in solid lines in Figure 1, the latch bar 20 is secured against pivotal movement on the shoulder rivet 22 by the circular cam face 40 which snugly fits into the annular recess 32 formed in the end portion of bar 20 above the pivotal axis.

In order to operate this latch it is necessary 30 that the operator grasp the operating arm 46, rotate it upwardly and about the pivotal member 38 until it extends downwardly as shown in dotted lines in Figure 1. As arm 46 approaches the downward position, the radially disposed boss 42 35 will contact the surface of the projecting tongue 34 to exert a pressure below the pivotal point 44. The weight of the arm 46 is not sufficient to 40 lift bar 20 so that the end of the stroke must be completed by means of the force exerted by the operator. When force is thus exerted the parts will take the position shown in Figure 4 with the bar 20 raised from the securing staple 28, and the arcuate portion of bar 20 extended into the recess 44 formed in the body of the cam member 36. These parts will remain in this position 45 only so long as the operator exerts the pressure against the bar 20. When he releases his hold the bar will drop back to the latching position with the arm 46 slightly inclined outwardly from the vertical.

This more or less complicated operation of the latch bar makes it almost impossible for the farm animal to dislodge the latching bar from the staple and if for an instant it is caused to take 50 the position shown in Figure 4, it will immediately

return to the latching position when the animal releases pressure against the cam parts.

This gate latch also precludes to a large degree the possibility of small children opening the gate, not only because the operation is quite complex, but because the force required to lift the latch bar is difficult for a child to exert.

It is quite apparent that this latching mechanism may be easily applied to fence gates, barn doors, etc. In fact, it is well adapted for use with substantially any horizontally swingable closure member.

While it is contemplated to use the latching means with the latch bar 20 normally in the horizontal position; however, in some instances, it might be advisable to incline the bar by mounting the base member diagonally on the gate stile. Instances requiring this type of mounting would be in cases where hogs might lift the gate on its hinges, thus raising the latch from the staple. However, if the latch slot 24 is properly inclined, it will strike the staple and preclude its removal therefrom.

What I claim as new and desire to protect by Letters Patent is:

1. A gate latch comprising a base plate, a latch bar pivoted to said base plate and having its free end portion adapted to engage a keeper, an arcuate cam pivoted to said base plate and normally operable through its major arc of movement to engage a notch in said latch member to secure said latch member against pivotal movement, and a boss carried by said cam and operable during the end portion of its stroke to pivot said latch bar, and operable to limit the movement of said cam in the opposite direction.

2. A gate latch comprising a base plate, a latch bar pivoted to said base plate and having an end portion adapted to engage a keeper, a cam pivoted to said base plate to move through the major arc of a circle, and having means engageable with said latch bar to maintain the bar against pivotal movement, and also having a projecting finger for engaging and raising said latch bar from said keeper during the final end travel of its stroke and for limiting the pivotal movement of said cam in the opposite direction.

3. A gate latch comprising a base plate, a latch bar pivoted to said base plate and having a free end portion adapted to engage a keeper whereby the gate is securely closed, a cam pivoted to said base plate and movable through more than a semi-circle without releasing said latch bar from said keeper, and having a finger to engage and raise said latch bar from engagement with said

keeper and to limit the pivoting of said cam in the opposite direction.

4. A gate latch comprising a base, a latch bar pivoted to said base plate and having a free end portion adapted to engage a fixed keeper whereby the gate is secured against opening, a cam pivoted to said base plate and having an arcuate edge adapted to engage and secure said latch bar in the keeper engaging position as the cam is rotated through more than 180°, and a radially disposed boss integral with said cam adapted to rest on top of said latch bar to limit the pivoting of the cam in one direction and adapted to engage the lower portion of said latch bar to raise the bar from engagement with said keeper.

5. A gate latch comprising a base plate adapted to be secured to the stile of a gate, a normally horizontally disposed latch bar pivoted adjacent one end for vertical movement to said base plate and being adapted to engage at its free end a fixed keeper secured to the gate to secure said gate closed, said latch bar being normally retained in engagement with said keeper by gravity, said latch bar being formed to present an arcuate notch disposed above said latch bar pivot, a substantially circular cam pivoted to said base plate concentrically with the normal position of said latch bar notch and adapted to enter said notch to lock said latch bar against movement, said cam having a single notch in its periphery which when disposed by pivoting said cam opposite said latch bar notch, permits the pivotal movement of said latch bar, and a single boss carried by said cam and adapted when said cam is turned in one direction to contact said latch bar to limit the movement of said cam, and adapted when turned in the opposite direction to contact the end of said latch bar below said latch bar pivot to pivot said latch bar upwardly against gravity and of engagement with its keeper.
